UNITED STATES PATENT OFFICE

WILLIAM A. BRANDT, OF DREXEL HILL, PENNSYLVANIA, ASSIGNOR TO AUTOMATIC ELECTRIC INC., OF CHICAGO, ILLINOIS, A CORPORATION OF DELAWARE

TESTING EQUIPMENT FOR AUTOMATIC TELEPHONE SYSTEMS

Application filed September 3, 1926, Serial No. 133,357. Renewed March 5, 1930.

The present invention relates to telephone systems.

More specifically, the invention is concerned with a recording device to be used in automatic telephone exchanges, for recording all calls extended to a predetermined line or station, regardless of whether the station or the line is busy or idle. A great number of traffic observation devices have been developed in the past, and are well known in the art, all more or less adequately meeting the requirements set up by the complex conditions confronting the modern telephone engineer. The value of traffic observation apparatus is now generally recognized, since it is well nigh impossible to cope with the progressing development in telephony without devices which give an accurate account of the amount of traffic routed over certain channels or to certain points, in a modern telephone exchange, with its multifarious, and frequently exceedingly complicated equipment. It may well be said that telephony has definitely passed the experimental stage, and that future developments will be, to a considerable extent, based on the results of traffic observation. Devices designed to record traffic have, therefore, become an indispensable tool in telephony.

One of the requirements of traffic observation is to record the total amount of traffic routed to a certain line or station. In other words, it is highly desirable to know how many calls are extended to a certain line or station within a predetermined time.

It is the chief object of the present invention to meet the requirements outlined above.

In accordance with this object, the invention is designed to record, on a pen-recorder, all calls extended to a predetermined subscriber's line, or other line, regardless whether the line is available or engaged in a connection previously completed.

However, it is not sufficient to record merely the number of calls extended to a certain line, or station, but it is of equal importance to record the length of time a line or a station is engaged, and the number of times the line, or station, is called while busy.

The necessity of this will be readily ap-

prehended if it is considered, that, as long as a conversation is carried on, a number of apparatus—(trunk lines and switches)—are withdrawn from traffic. Since the switches and the trunk lines over which a call is extended are common to a large part of the remaining exchange equipment, it will be obvious that the holding time, that is, the period for which the various apparatus are engaged, is just as important as the frequency with which they are taken into use.

Accordingly, it is also an object of the invention, to record the length of time of each successful call terminating at a certain line or station, and the length of time of each subsequent call extended to that line or station while busy. To explain this a little more in detail, when a line or station is called while busy, the calling party receives a busy signal. However, as each person has his individual persistency, the time until a calling party restores the receiver to the switch hook, in response to the busy signal, will vary with each case. It is, of course, not only of general interest, but of utmost importance to have an accurate record of the holding time of a non-successful extension.

Throughout the preceding paragraphs, reference was made to "lines or stations" which the present invention proposes to observe and to record the amount of traffic routed to them. The preservation of flexibility being an essential object of the invention, the same was designed with the view of furnishing a portable device for observing subscribers' stations, as well as trunk lines, in fact, any line accessible from an automatic switch. The phrasing "line or station", or equivalent terminology employed in this specification has to be understood in this sense. Accordingly, the recording equipment disclosed, may be employed for observing a certain subscriber's station, by connecting it up with all the connectors which have access to that station, or if slightly modified, it may be used for observing a certain trunk line accessible to automatic switches, by connecting it up with these switches.

The utility of the invention will be appar-

ent from the detailed explanation which is yet to follow, and which should be read in connection with the single sheet of drawings, which forms a part of the specification. 5 However, before entering a detailed discussion, it will be advisable to give a brief account of the figures shown in the drawing.

Stated generally, Fig. 1 shows a recorder as intimated in the above paragraph, and 10 Fig. 2 shows schematically how such recorder is connected up in practice. Details of the figures shown, and symbols used in the figures will now be explained more particularly.

In Fig. 1, is shown the recording device, 15 comprising the relays 1-5, inclusive; a small rotary switch M with its motor magnet 6, release magnet 7, and wiper 8; 9 is the off-normal contact operated by the switch M; 10 and 11 are two conductors by means of 20 which the observation of a certain line or subscriber's station is adjusted; 12 and 13 are conductors to be connected up with a common pen-recorder; 14 is a plug for connecting the device to a connector or to another switch which has access to the line under observation; 22 is a common signal device 25 which is actuated in case of a faulty operation.

Fig. 2, illustrates schematically how the 30 recording device, shown in Fig. 1, is used in practice. It is assumed in this figure that a certain line is to be observed, and that this line is accessible to ten switches, 26-35. A device, such as the one shown in Fig. 1, will 35 be connected up by means of a plug with each of these switches, the connections being indicated by leads 36-45 inclusive, and the recording devices being shown at 46-55 inclusive. All these recording devices are 40 connected up with a common pen recorder 56 which is equipped with as many pens as there are recording devices. It being assumed that there are ten recording devices, the common pen recorder will be equipped 45 with ten pens designated 57 to 66 inclusive (only the first two and the last pen being shown in the drawing). All pens record on the common paper tape 67.

Throughout the drawing Fig. 1, there are 50 shown a plurality of ground and battery connections. It will be understood, however, that this has been done only for convenience of description and that there is only one battery in practice, preferably the 55 exchange battery, which may be connected to the recording apparatus in any well known and approved manner.

The automatic switch, having access to a certain line which is to be observed, has not 60 been shown, in order to keep the drawing as simple as possible. Those switches are well known to every one familiar with telephony. Each of these switches is equipped with a test jack, which is utilized in the present case for 65 connecting up the recording apparatus.

Having given a general account of the invention, and a detailed account of the drawings and symbols used, a detailed description of the disclosure will now be proceeded with. It shall be assumed, for this purpose, that all calls extended to a certain subscriber's telephone line shall be recorded and that this line is accessible to a number of connectors as indicated in Fig. 2. Accordingly, the portable recording apparatus is moved to the 75 board containing these connectors, and the devices are connected up by means of plugs, such as 14.

Each of the subscribers' lines accessible to these connectors can be reached by operating 80 any one of the connectors in accordance with the last two digits of the directory number. It shall be assumed, that it is desired to record the calls extended to a subscriber's line whose 85 telephone number ends with two digits of the same numerical value, for example 4-4.

The lead 10 is connected, in this case, to contact 4 of the switch M; the lead 11 is left open, and lead 13 is connected to a corresponding 90 pen in the common pen recorder. This adjustment is made in all of the recording devices, 46-55, inclusive, shown in Fig. 2.

When a connector is seized, its release conductor is grounded in the usual manner. Since a recording apparatus, such as the one 95 shown in Fig. 1, is connected up with each connector, by means of plug 14 which is inserted into the test jack of the connector, this ground will cause the operation of relay 3. The relay operates its armature 17, thereby 100 opening a point in the release circuit of the switch M.

Relay 1, which is a polarized relay, is connected in series with a condenser, in bridge 105 of the talking conductors of the connector switch. Accordingly, this relay operates in response to the impulses delivered to the connector. In response to the first digit, relay 1 110 will intermittently operate its armature 15, thereby producing current impulses for operating the magnet 6 of the switch M, from battery in series with relay 2. The latter, 115 being a slow acting relay, remains energized during impulsing. It opens its armature 16, removing ground from the wiper 8, and closes 120 its armature 21, connecting ground to a common slow acting signal device 22. If the 125 rotary—(and as will be seen later, also the release)—operation is faulty, this signal device 130 will be operated at the termination of a certain period of time. The wiper 8 of switch M advances as indicated by the arrow.

If the digit delivered to the connector is anything but four, nothing happens on the recording device, except that the wiper 8 remains on the contact to which it was advanced. When the connector releases, the wiper returns to normal position, due to the circuit 135 for the release magnet 7 being closed at the release of relay 3, from ground, off normal 140

springs 9, back contact and armature 17, release magnet 7, slow acting relay 2 to battery. If the operation is proper, the switch M releases immediately, opening the release circuit at its off normal springs 9; if faulty, the release circuit and with it the relay 2 will remain closed for an abnormal time, and the signal device 22 will operate, as was intimated in the preceding paragraph.

However, if the first digit is four, which is the first digit of the number to be observed, the wiper 8 is advanced to contact 4. The relay 2 releases during the interval between the digits, and closes a circuit for the operation of relays 5 and 4, from ground, back contact and armature 16, wiper 8, contact 4, lead 10, armature 19 and its back contact, relay 5, upper winding of relay 4 to battery. Relay 4 locks itself over its lower winding and armature 23 to ground on the release trunk, and connects the lead 10 through, to the pen recorder, over its armature 19, thereby disconnecting relay 5. The latter relay, while operated, closes a circuit for releasing the switch M, from ground, front contact and armature 20, release magnet 7 and relay 2 to battery.

When the next digit is delivered to the connector the switch M is again advanced as previously explained. Now, if this digit is anything but four, nothing will happen until the apparatus is released when the connector is freed. However, if this digit is also four, the wiper 8 will again step to the fourth contact. Relay 2 restores shortly after the termination of the impulses and closes a circuit over its armature 16, wiper 8, contact 4, lead 10, armature 19 and its front contact, lead 13, to the corresponding pen. This last circuit will persist throughout the duration of the connection. The pen recorder will record the call.

If the subscriber's telephone number ends in two digits of a different numerical value, such as 3-1 or 8-4, etc., the lead 10 is connected to the contact corresponding to the first digit, while the lead 11 is connected to the contact corresponding to the second digit. In this case, the lead 12 is connected to the pen in the common pen recorder. The operation is then substantially the same as already explained, i. e., the switch wiper 8 is advanced, in response to the first digit delivered to the connector, to the corresponding contact in the bank of switch M. Relay 2 deenergizes after the termination of the first digit and connects ground by means of its armature 16 to the switch wiper 8, thereby effecting the operation of relays 5 and 4. Relay 4 locks itself over its lower winding and armature 23 to the release trunk, disconnecting relay 5. During the time relay 5 is in operated position, with its armature 20 closed, the release circuit for the switch M is completed as before. In response to the second digit, the

switch wiper 8 is advanced to the corresponding contact, to which is now connected the lead 11. Relay 2 releases at the termination of the impulses, completing the circuit for the pen recorder from ground, back contact and armature 16, wiper 8, lead 11, armature 18 and its front contact, and lead 12.

Relay 2 is common to both, the rotary and release circuit, and removes ground from the wiper when either is operated, in accordance with the usual practice to remove potential from a wiper while it brushes over the bank contacts.

As each connector is temporarily associated with a recording device, it will be readily seen, that all calls extended to the line or trunk under observation will effect the operation of the recording apparatus in the manner described. All calls will therefore be recorded on the pen recorder. An inspection of the tape will show series of dashes. The number of these dashes will correspond to the number of connections to the line or trunk under observation. It will be seen that the length of time a connector is occupied on this number will determine the length of a dash on the tape. If, while the line is busy, a connector establishes connection with this line, the calling subscriber receives a busy tone. While the subscriber is listening to the busy signal the pen recorder will record the time. Busy calls will therefore show dots or small dashes on the tape, as usually the calling party hangs up soon after the busy signal is received. Therefore, the tape will furnish an excellent record, both of the holding time and number of times a line was called when busy. In other words, successful as well as unsuccessful calls will be recorded both as to the holding time of the switches and as to the frequency of occurrence.

It will be seen from the above description that the present invention is simple in its application and represents an excellent means for recording calls extended to a line or trunk. While there is shown only one way of carrying out the invention, many other applications will readily suggest themselves. It is therefore requested that the interpretation of the invention is not limited by the precise structure disclosed, but only by the claims which follow.

What is claimed is:

1. In a telephone system, lines, means for extending connections from calling lines to a called line, and means for recording any call and the duration of any call extended to said called line, regardless of whether said line is busy or idle.
2. In a telephone system, lines, means for extending connections from calling lines to a called line, means for recording the duration of each successful connection, and means for recording the duration of calls extended to said called line while said line is busy.

3. In a telephone system, lines, means for extending connections from calling lines to a certain called line, means for recording the duration of each successful connection, and means for recording the waiting times of calling lines attempting to establish connection with said certain called line while said line is busy.
4. In a telephone system, lines, means for extending connections from calling lines to a certain called line, a recorder including a moving tape, means for recording on said tape the duration of each connection, and means for recording on said tape all calls extended to said certain called line while said line is busy.
5. In a telephone system, lines, means for extending connections from calling lines to a certain called line, a plurality of recorder units adapted to operate a common pen recorder having a moving tape, means for recording on said tape the duration of each successful connection, and means for recording on said tape the waiting times of calling lines desiring to establish connection with said certain called line while said line is engaged in a connection previously completed.
6. In a telephone system, a plurality of automatic switches, a called line accessible to said switches, a portable recording device, means for temporarily associating said device with said switches and means associated with said device for recording any call extended to said called line, regardless of whether said line is busy or idle.
7. In a telephone system, calling lines, a called line, a plurality of automatic switches accessible to said calling lines for extending calls to said called line, a portable recording device, means for temporarily associating said device with said switches, means in said device for operating the same under control of a calling line, and means associated with said device for recording the duration of each call extended to said called line, regardless of whether said line is busy or idle.
8. In a telephone system, calling lines, a plurality of automatic switches, a called line accessible to said switches, a portable recording device, means for temporarily associating a recording device with each one of said switches, a plurality of relays associated with each device, means for operating said relays under control of a calling line, and means in said device responsive to said relay for recording any call extended to said called line, regardless of whether said line is busy or idle.
9. In a telephone system, a plurality of automatic switches, called lines accessible to said switches, a portable recording device, means for temporarily associating said device with said switches, and means in said device for recording the total number of calls and the duration of each call extended to a certain line, regardless of whether said line is busy or idle.
10. In a telephone system, a plurality of automatic switches, called lines accessible to said switches, a portable recording device, means for temporarily associating said device with said switches, and means associated with said device for recording the total amount of time consumed by each of said switches in holding established extensions to a predetermined called line, regardless of whether said line is busy or idle.
11. In a telephone system, a plurality of automatic switches, called lines accessible to said switches, a portable recording device, means for temporarily associating said device with said switches, a pen recorder associated with said device, and means in said device controlled by a calling line for actuating said pen recorder to record the total amount of time consumed by each of said switches in holding established extensions to a predetermined called line, regardless of whether said line is busy or idle.
12. In a telephone system, a plurality of automatic switches, called lines accessible to said switches, a portable recording device having a plurality of control units, means for temporarily associating said units with said switches, a pen recorder associated with said device having a plurality of pens in number corresponding to said units, and means in each of said units controlled by a calling line for actuating one of said pens in said pen recorder to record the total amount of time consumed by each of said switches in holding established extensions to a predetermined called line, regardless of whether said line is busy or idle.
13. In a telephone system, a plurality of automatic switches, called lines accessible to said switches, a portable control device having a plurality of control units, means for temporarily associating said units with said switches, a recording apparatus associated with said device, means in said units controlled by a calling party to actuate said apparatus for recording the total amount of time consumed by each of said switches in holding established extensions to a called line, regardless of whether said line is busy or idle, and means in said control units for predetermining the line for recording the traffic thereover.
14. In a telephone system, lines, substation controlled switches having access to said lines, a polarized relay, a recording device arranged to co-operate with said relay, means for temporarily associating said relay with any one of said switches, and means actuated by said relay for operating said device to record extensions to predetermined lines regardless of whether said lines are busy or idle.
15. In an automatic telephone system, a

plurality of switches having common access to called stations, test jacks for said switches, a plurality of control devices, means for associating said devices with said switches by means of said jacks, a recording apparatus common to said devices and associated therewith, and means in said control devices for actuating said recording apparatus to record the total time said switches consume in calls to a predetermined line, regardless of the busy or idle conditions thereof.

16. In a telephone system, a plurality of automatic switches operated by impulses transmitted thereto over calling lines, a certain called line accessible to each of said switches and connected thereto when any one of said switches is operated by a predetermined number of impulses, a recording device, and means associated with each of said switches for counting the impulses transmitted thereto, said means operating said recording device when the number of impulses transmitted is said predetermined number, to make records of the connections to said called line.

17. In a telephone system, an automatic switch operated by impulses transmitted thereto over a calling line, a certain called line accessible to said switch and connected to when said switch is operated by a predetermined number of impulses, a counting switch associated with said automatic switch and operated in synchronism therewith to count the impulses received thereby, a recording device, and means operated by said counting switch when said automatic switch receives said predetermined number of impulses for operating said recording device to record the connection to said called line by said automatic switch.

18. In a telephone system, a two-motion switch directly operated by series of impulses over a calling line, a certain called line accessible to said switch and connected thereto when said switch is operated by two predetermined impulse series, a recording device, a rotary switch having a normal position and operated in synchronism with said two-motion switch for counting the impulses of all series received by said two-motion switch, and means operated by said rotary switch when the first of said two predetermined impulse series has been received for preparing said recorder for operation and for returning said rotary switch to its normal position, said rotary switch responsive to the reception of the second of said predetermined impulse series for operating said recording device to record the connection to said called line by said two-motion switch.

19. In a telephone system, a pair of automatic switches operated simultaneously by impulses transmitted thereto over a calling line, a called line accessible to one of said switches and connected thereto when said

switches are operated by a predetermined number of impulses, and means operated by the other of said switches when said switches are operated by said predetermined number of impulses, for recording the connection of said one switch to said called line.

20. In a telephone system, a pair of automatic switches directly operated simultaneously by the same two series of impulses transmitted thereto over a calling line, one of said switches having a normal position, a called line accessible to the other of said switches and connected thereto when said switches are operated by two predetermined impulse series, automatically operating means for returning said one switch to its normal position after the transmission of the first series of impulses, and means prepared for operation and then operated by said one switch when it is operated by said two predetermined impulse series, for recording the connection of said other switch to said called line.

In witness whereof, I hereunto subscribe my name this 28th day of August, A. D. 1926.

WILLIAM A. BRANDT.
